Attorney.

UNITED STATES PATENT OFFICE.

VERNON GEORGE CONVERSE, OF PITTSBURG, PENNSYLVANIA, ASSIGNOR
TO THE HEMINGRAY GLASS COMPANY, OF COVINGTON, KENTUCKY.

DESIGN FOR AN INSULATOR.

SPECIFICATION forming part of Design No. 30,637, dated April 25, 1899.

Application filed February 27, 1899. Serial No. 707,086. Term of patent 14 years.

To all whom it may concern:

Be it known that I, VERNON GEORGE CONVERSE, a citizen of the United States, and a resident of Pittsburg, in the county of Allegheny and State of Pennsylvania, have invented and produced a new and original Design for Insulators, of which the following is a specification, reference being had to the accompanying drawings, forming part thereof.

5. Figure 1 is a side view of an insulator, showing my new design. Fig. 2 is a vertical section taken through the center of same.

As shown in the drawings, the leading or material features of my design consist of the 5 horizontal petticoats *a*, the vertical petticoats

b, and the flaring base or shield *c*, arranged as shown in the figures, the petticoats being so arranged as to produce grooves intermediate the petticoats.

The insulator is provided with the screw-threaded socket for the supporting-pin.

Having thus described my invention, what I claim as new, and desire to secure by Letters Patent, is—

The design for an insulator, substantially 25 as shown and described.

VERNON GEORGE CONVERSE.
